UNITED STATES PATENT OFFICE.

DANIEL P. SENGER, OF MINOT, NORTH DAKOTA.

EARTH SCOOP.

Application filed September 17, 1925. Serial No. 56,997.

To all whom it may concern:

Be it known that I, DANIEL P. SENGER, a citizen of the United States, residing at Minot, in the county of Ward and State of North Dakota, have invented certain new and useful Improvements in Earth Scoops; and I do declare the following to be a full, clear, and exact description of the invention, such as will enable others skilled in the art to which it appertains to make and use the same.

The invention relates to improvements in horse-drawn or tractor-drawn scoops of the type which is not provided with wheels, but merely slides along the ground, and the invention resides primarily in novel dumping means for such a scoop.

One object of the invention is to provide a dumping means which may be easily and inexpensively manufactured and may be readily applied to a scoop, the construction being such that this dumping means may be readily brought into play whenever desired.

The dumping means includes a pair of earth-engaging, scoop-dumping arms disposed at the sides of the scoop, and a further aim is to provide unique guiding yokes for these arms, which yokes prevent lateral displacement of the arms as well as limiting their upward and downward movements.

Figure 1 of the accompanying drawings is a side elevation of a scoop embodying the invention, showing the relation of parts when the load is being collected or hauled.

Figure 2 is a view similar to Fig. 1 but illustrating the manner in which the dumping means is active to cause overturning of the scoop to discharge its contents.

Figure 3 is a top plan view.

Figure 4 is a vertical transverse section on line 4—4 of Fig. 1.

I have shown my improvements in connection with a scoop or scraper of the well known Fresno type, in which the opposed side walls S of the scoop are provided with runners R, said runners being connected by a transverse bar B which extends over the scoop body. Projecting rearwardly from the rear wall W of this scoop body, the usual handle H has been shown.

Transversely alined bearings 1, of any suitable form, are secured to the rear side of the wall W, and in these bearings a transverse rock shaft is mounted, said shaft preferably comprising two sections 2 and 3, the inner end of the section 2 being bent rear-

wardly to provide a handle 4 disposed adjacent the handle H, while the inner end of the shaft section 3 is rearwardly bent as at 5 and secured by bolts or the like 6 to the front portion of said handle 4. The outer ends of the shaft sections 2 and 3 are provided with forwardly projecting scoop dumping arms 7, preferably formed integrally with said shaft sections, as shown. 65 These arms are disposed at the sides of the scoop and they pass through guide yokes 8 which hold them against lateral displacement and limit their upward and downward movements. Coiled, tension springs 9 have 70 their lower ends suitably connected at 10 with the arms 7, while the upper ends of said springs are attached, in the present disclosure to the bar B. These springs exert their tension to normally raise the arms 7 75 against the upper ends of the yokes 8, but when the handle 4 is pulled upwardly, the front ends of said arms 7 are caused to move downwardly, so that they can penetrate the earth and cause easy dumping of the scoop, 80 it being of course understood that the latter is provided with any of the well known draft means by which the real dumping operation is effected when the front end of the scoop is held against forward movement by 85 the arms 7. Each of the yokes 8 comprises a vertical upper portion 11, and a vertical lower portion 12 laterally offset from said upper portion. The portion 11 lies against the outer side of the wall S and has its 90 upper extremity bent laterally inward as at 13 over the upper edge of said wall, and then bent downwardly as at 14 into contact with the inner side of the wall. The lower extremity of the portion 12 is bent laterally 95 inward toward the wall S as indicated at 15, is then bent at right angles in another direction, preferably upwardly, to provide a shoulder 16 which abuts the outer side of the wall S, and is finally bent again inwardly to provide an attaching stud 17, which stud passes through an opening 18 in the wall S and is provided on its inner end with a nut 19 or some other adequate shoulder. By constructing the yoke in this manner, it may be easily and inexpensively manufactured, quickly and easily attached, and will well perform the functions for which it is designed.

As excellent results are obtainable from the details herein disclosed, such details are preferably followed. However, within the

scope of the invention as claimed, modifications may of course be made.

I claim:

- 5 1. In a scoop having a rearwardly projecting handle; a transverse rock shaft mounted on the back wall of said scoop and provided with a rearwardly projecting handle, scoop-dumping ground-engaging arms projecting forwardly from said rock shaft
- 10 at the sides of the scoop, yokes carried by said sides of the scoop, said arms passing through said yokes for vertical movement, and spring means for normally raising said arms against the upper ends of the yokes.
- 15 2. In a scoop having a rearwardly projecting handle; and provided with runners at its sides connected by a transverse bar; a transverse rock shaft mounted on the back wall of said scoop and provided with a rearwardly projecting handle, scoop-dumping ground-engaging arms projecting forwardly
- 20 from said rock shaft at the sides of the scoop, yokes carried by said sides of the scoop, said arms passing through said yokes for vertical movement, and tension springs
- 25

connecting said arms with the ends of said transverse bar to normally raise the arms against the upper ends of the yokes.

3. In a scoop having ground-engaging dumping arms at its sides; guiding yokes for said arms each comprising a single metal rod having an upper portion lying against a side wall of the scoop and a lower portion outwardly offset from said upper portion, the upper extremity of said upper portion being bent laterally inward over said wall and then downwardly in contact with the inner side of said wall, the lower extremity of said lower portion being bent laterally toward said wall, then bent in another direction to provide a shoulder contacting with the outer side of the wall and then bent again laterally to form an attaching stud, the latter passing through the wall and having a shoulder engaging the inner side of said wall.

In testimony whereof I have hereunto affixed my signature.

DANIEL P. SENGER.
